CIRCUIT-ARRANGEMENT COMPRISING A FREQUENCY-STABILIZED OSCILLATOR

Louis Raymond Bourgonjon, Hilversum, Netherlands, assignor to Hartford National Bank and Trust Company, Hartford, Conn., as trustee

Application May 18, 1953, Serial No. 355,778

Claims priority, application Netherlands May 17, 1952

3 Claims. (Cl. 250—36)

The present invention relates to circuit arrangements for stabilizing the frequency of an oscillator. More particularly, the invention relates to circuit-arrangements comprising an oscillator and equipped with an AFC-circuit for automatic stabilization of the oscillator frequency relatively to a control frequency, more particularly relatively to a component of the frequency spectrum of a pulse-shaped control voltage, which component is chosen by initial tuning of the oscillator, the said AFC-voltage controlling a reactance tube coupled to the oscillator.

It is known to furnish such arrangements with a search voltage generator which, in the absence of stabilization of the oscillator frequency, produces an oscillator-frequency variation by means of a low-frequency search voltage with a view to extending the collecting zone of the AFC-circuit.

Circuit-arrangements of this type have been proposed in United States Patent No. 2,725,476, issued November 29, 1955, to Hugenholtz, in which, for extending the collecting zone, the extreme anode direct voltage of the reactance tube, which voltage occurs in the absence of stabilization, serves to energize a sawtooth generator comprising a glow discharge tube, the search voltage thus produced causing the reactance tube to traverse the whole control range. In this instance, collection takes place only during the slow edge of the sawtooth search voltage and difficulties of a practical nature are experienced in trying to obtain a sufficiently constant very low search frequency.

An object of the present invention is the provision, in arrangements of the type referred to in the preamble, of a simple and particularly suitable search voltage generator for widening the collecting zone, which generator produces a sinusoidal voltage having a very low frequency.

In accordance with the invention, the search voltage generator comprises the reactance tube fed back by way of a feedback loop comprising an auxiliary amplifier tube and a circuit determining the search voltage frequency.

For mutual decoupling of the AFC-circuit and the search voltage circuit on supplying the AFC-voltage to the control grid of the reactance tube, the coupling of the auxiliary amplifying tube to the reactance tube may be established by a cathode resistor which both tubes have in common and is capacitatively with respect to oscillator frequencies.

As a reactance tube use is preferably made of a multi-grid tube, the oscillator voltage being applied to the control grid, and the feed-back loop being connected between the anode of the reactance tube and another grid. The use of two separated grids in the reactance tube for AFC-control and introduction of the search voltage into the reactance tube, respectively, is highly beneficial to the stability of the circuit-arrangement.

The network determining the search voltage frequency preferably consists of resistors and capacitors connected in such a manner that the reactance tube and the auxiliary

2

amplifying tube jointly constitute a so-called Wien-bridge-generator. As is known, the frequency constancy of such an RC-generator is particularly favorable. The RC-generator circuit in accordance with the invention is adapted, as will be explained with reference to the drawing, to be substantially decoupled with respect to the oscillator frequencies. This is particularly advantageous for stability reasons.

In order that the invention may be readily carried into effect, it will now be described with reference to the accompanying drawing, wherein the figure is a schematic diagram of an embodiment of the circuit arrangement of the present invention.

The circuit-arrangement of the figure comprises a high-frequency oscillator 1 which is tunable in a range of, for example, 1.5 to 4 megacycles per second. The oscillator tube comprises a hexode portion 2 of a triode-hexode 3. The anode of the hexode is connected through a tunable anode circuit 4 to the positive junction terminal 5 of an anode voltage source (not shown). Coupled to the anode circuit is a feedback coil 6 coupled in the control grid circuit of the hexode.

The anode of the oscillator hexode 2 is connected directly to the anode of a pentode 7 forming part of a reactance tube circuit 8, which is of usual design and comprises a feedback capacitor 9 provided between the anode and the control grid of said pentode. To the control grid of the reactance tube 7 is applied, by way of a lead 10, an AFC-voltage required for stabilizing the frequency of the high-frequency oscillator 1. The AFC voltage is applied in such manner that the oscillator frequency is stabilized relatively to a higher harmonic of a pulse voltage from a crystal-controlled pulse generator 11; said harmonic being chosen by initial tuning of the anode circuit 4. The required AFC-voltage is obtained by mixing, in a mixer stage 12, the voltage set up at the oscillator control grid with the output voltage of the pulse generator 11. The mixer stage 12 is normally blocked and is released only during the occurrence of a pulse. Said mixer stage acts as a phase-detector and supplies, via an integrating network 13 and a low-pass filter 14, an AFC-voltage consisting, upon stabilization of the high-frequency oscillator 1, of a direct voltage and, failing stabilization, of an alternating voltage whose frequency corresponds to the frequency difference of the oscillator voltage and the frequency adjacent spectrum component of the pulse voltage. For various reasons, such as for avoiding instability of the AFC-circuit, the filter elements 13, 14 are so proportioned that only comparatively low difference frequencies, for example having maxima of a few kilocycles per second or only a few hundreds of cycles per second, are transmitted substantially non-attenuated via the lead 10 to the reactance tube circuit 8. These frequencies thus provide frequency-modulation of the high-frequency oscillator 1 until the collection point is passed. In this instance, the oscillator frequency is automatically locked on the neighboring higher harmonics of the impulse spectrum of the pulse generator 11.

The collecting zone of the AFC-circuit is extended by means of a search voltage generator. In order to establish the search voltage generator circuit, a feedback loop is provided between the anode and the screen grid of the reactance tube 7. Said feedback loop comprises a triode 15 as an auxiliary amplifying tube and a phasing network, consisting of resistors and capacitors, as the element determining the search voltage frequency. The triode 15 forms part of the triode-hexode 3, whose hexode portion serves as an oscillator tube. The anode of the reactance tube 7 is connected through a high-frequency choke 16 to an input terminal of a

four-terminal network grounded at its input and output end, whose series impedance consists of the series-connection of a resistor 17 and a capacitor 18, and whose parallel impedance between the output terminals consists of the parallel-connection of a resistor 19 and a capacitor 20. Connected between the input terminals of said four-terminal network 17 to 20 is a capacitor 21 which constitutes a short-circuit with respect to the oscillator frequencies. The non-grounded output terminal of the four-terminal network is connected to the control grid of the triode 15. The anode of triode 15 and the screen grid of the reactance tube 7 are directly connected to each other and across a common resistor 22 with a decoupling capacitor 23 to the positive junction terminal 5 of the anode voltage source. Thus, part of the reactance tube 7, the triode 15 and the RC-network 17 to 20 jointly constitute a so-called Wien-bridge-generator with the RC-four terminal network 17 to 20 as a frequency-determining element. The latter may, for example, be so proportioned as to cause the RC-generator to oscillate with a frequency of a few cycles per second.

The RC-generator as described generates only if the high-frequency oscillator 1 is not locked on a spectrum component, since in locked condition, the reactance tube 7 does not respond to variations of the screen grid voltage. That is, said variations cause practically no anode voltage variations as required for causing self-oscillation of the RC-generator. Due to the associated variation of the apparent reactance of the reactance tube circuit 8, screen grid voltage variations would involve variation of the oscillator frequency. Variation of the oscillator frequency is counteracted by the frequency-stabilizing AFC-circuit and thus compensates the influence of the screen grid voltage variation on the anode current of the reactance tube 7. In other words, the reactance tube, in locked condition is negatively fed back to a degree such that the influence of its positive feedback through a triode 15 is offset and the RC-generator is inoperative.

In the absence of locking, however, the RC-generator produces a sinusoidal search voltage, with the result that the mutual conductance of the reactance tube circuit 8, and consequently the frequency of the high-frequency oscillator 1, vary in the rhythm of the search voltage frequency. The high-frequency oscillator 1 then "searches," starting with the tuning frequency of the anode circuit 4, a frequency range of, for example, approximately 50 kilocycles per second, until collection and locking occurs.

As stated above, the input of the RC-four-terminal network 17 to 20 is decoupled by means of the choke 16 and the short-circuiting capacitor 21 with respect to the oscillator frequencies. The output of said RC-four-terminal network is also short-circuited with respect to the oscillator frequencies by the capacitor 20 connected between the output terminals. Owing to this, the usual connection of the control grid of the triode 15 to the second control grid of the hexode 2 in the triode-hexode tube 3 cannot cause trouble. Due to the decoupling capacitor 23, high frequency voltages will occur neither at the anode of the triode 15 nor at the screen grid of the reactance tube 7. As a result of the said decoupling steps the RC-generator circuit is highly decoupled relatively to the oscillator- and reactance-tube circuit and said circuits do not adversely affect each

other. After locking the frequency of the high-frequency oscillator 1 on a spectrum component of the pulse voltage of the pulse generator 11, the search voltage generator will be fully inoperative. The desired oscillator voltage occurs across the anode circuit 4 and may be supplied to a load via a coupling capacitor 24.

The invention may also be used if the oscillator frequency is stabilized relatively to a sinusoidal control voltage instead of a pulse-shaped control voltage. In this case a sine wave generator instead of the pulse generator 11 is connected to the mixer stage 12; the search voltage generator circuit may remain unchanged.

It is to be understood that the invention is not limited to the details disclosed but includes all such variations and modifications as fall within the spirit of the invention and the scope of the appended claims.

What is claimed is:

1. A system for stabilizing a first voltage produced by a controllable oscillator with respect to a second voltage produced by a reference oscillator comprising a phase discriminator for comparing said first voltage with said second voltage and producing therefrom a control voltage depending on the frequency difference therebetween, a voltage-responsive frequency control device including a reactance tube having an anode, a control grid and a screen grid coupled to said controllable oscillator, means for applying said control voltage to said reactance tube to vary the frequency of said controllable oscillator in a direction effecting synchronization with said second voltage, and a search voltage generator producing a low-frequency search voltage for varying the frequency of said controllable oscillator in the absence of synchronization, said generator including said reactance tube and a feedback circuit coupled to said tube and comprising a four-terminal network having input terminals and output terminals, a series impedance including a first resistor and a first capacitor serially connected thereto and a parallel impedance including a second resistor and a second capacitor shunted thereby, a high frequency choke coupling said anode to one of said input terminals, a short-circuiting capacitor for said first voltage connected between said input terminals, and an auxiliary amplifying tube having an anode and a control grid, said control grid being connected to one of said output terminals.

2. A system, as set forth in claim 1, further including a common resistor coupling a source of anode voltage to the anode of said auxiliary amplifying tube and to the screen grid of said reactance tube.

3. A system, as set forth in claim 2, wherein said auxiliary amplifying tube consists of a triode and said controllable oscillator includes an oscillator tube consisting of a hexode and wherein said triode and said hexode constitute a triode-hexode tube.
